ALFRED DUVALL, OF BALTIMORE, MARYLAND.

Letters Patent No. 86,289, dated January 26, 1869.

IMPROVED METHOD OF MIXING LIQUIDS WITH DUST OR POWDER FOR THE MANUFACTURE OF PHOSPHATES, AND FOR OTHER PURPOSES.

The Schedule referred to in these Letters Patent and making part of the same.

To all whom it may concern:

Be it known that I, ALFRED DUVALL, of Baltimore, in the county of Baltimore, and State of Maryland, have invented a new and useful Improvement in the Method of Vitriolizing (or mixing with acids or liquids of any kind) Granulated or Pulverized Phosphates, or any other pulverized substance, and, when necessary or desired, for quickly precipitating the finest pulverized matter in a receiver; and I do hereby declare that the following is a full, clear, and exact description of the construction and operation thereof, reference being had to the accompanying drawing, and letters of reference thereon, making a part of this specification, in which the figure is a longitudinal section in elevation, being the only drawing deemed necessary to fully illustrate the principles involved.

To enable others skilled in mechanics to make and use my invention, I will proceed to describe the construction and operation of the same.

The character of my invention, as shown by the accompanying drawing, and described in this specification, consists in using a jet of steam or blast of air, created by a fan or otherwise, blowing against or in contact with a column of vitriol, or other liquid, and the granulated or pulverized matter being treated, whether exhausted from a mill while being pulverized, or descending from a spout and falling in contact with the liquid used and the blast of steam or air.

A is the pipe, through which the material being treated is blown or exhausted, and into which the acid or liquid used passes, as also the blast of steam or air.

B, the spout, through which the granulated or pulverized matter, when not exhausted, falls into the pipe A, near the point of discharge.

C, the pipe, for conducting the vitriol or other liquid into the pipe A.

D, a valve, in the pipe C, by which the quantity of liquid being used is regulated or shut off entirely.

E, a steam-pipe, connecting with the pipe A.

F, a valve, in the steam-pipe E.

G, a fan, with a pipe, H, connecting with the pipe A.

I, a receiving-chamber, in which the matter being treated is precipitated.

J, a pulverizing-mill or chamber, connecting with the reverse end of the pipe A.

Operation.

The steam or air, whichever is being used, is forced into the pipe A, creating a blast. The granulated or pulverized matter being treated and the liquid being used are then let into the pipe A, through the pipes B and C, and, by means of the blast, are thoroughly mixed and blown into and precipitated in the receiving-chamber I. If exhausting from a mill or chamber, J, connected with the pipe A at the reverse end of the arrows, the pulverized matter from that point is exhausted, mixed, and precipitated in the chamber I. As will be understood from the foregoing description, the operation of mixing and precipitating may be carried on at the same time from the spouts B and C and the pulverizing-mill or chamber J at the reverse end of the pipe A.

What I claim as my invention, and desire to secure by Letters Patent, is—

The principles involved, for the purpose intended, as shown by the accompanying drawing, and described in the foregoing specification, or any modification thereof, of involving the same general principles of construction or operation.

Witnesses:

ALFRED DUVALL.

J. Y. ELY,

A. LESLIE DUVALL.
